UNITED STATES PATENT OFFICE.

JAMES WHITE, OF BROOKLYN, ASSIGNOR TO THE TWIST PIPE COMPANY,
OF NEW YORK, N. Y.

JOINTING ROOFING-SHEETS.

SPECIFICATION forming part of Letters Patent No. 511,386, dated December 26, 1893.

Application filed March 26, 1892. Renewed May 29, 1893. Serial No. 475,982. (No model.)

To all whom it may concern:

Be it known that I, JAMES WHITE, a citizen of the United States, residing at Brooklyn, Kings county, New York, have invented certain new and useful Improvements in Jointing Roofing-Sheets, fully described and represented in the following specification and the accompanying drawings, forming a part of the same.

10 The object of this invention is to furnish an expansible or yielding joint for the edges of roofing sheets and to anchor the joint securely to the roof. This object I accomplish by forming flanges upon the roofing sheets, 15 with inclined sides, and edges projected above the level of the sheet, and adapted to overlap upon a wooden strip. The lapped joint of two edges is secured by nails and covered by a cap which is held in place without nails, 20 and therefore without perforating the same. The strip of wood may be made with a grooved or a flat top, the groove being preferred, as it locks the edges of the flanges upon the strip and thus helps them to resist any lateral strain.

25 The strips are secured to the roof before or after the edges of the sheets are lapped thereon, and the flanges are nailed to the strips so that the roofing sheets are securely anchored to the roof. The expansion of the sheet is 30 absorbed by the sloping sides of the flange, and the joint is thus protected from the strains of expansion and contraction. When the joint is exposed to the weather the cap is made wide enough to cover the highest 35 portion of both flanges, and has its edges turned down to throw the water upon the sloping sides, and in such case, the cap is held in place by narrow cleats, first secured transversely across the joint, with their ends bent 40 over the edges of the cap to hold the latter in place. Where the joint is not exposed to the weather, as in the case of "sidings," the cap may be made narrower than the top portion of the flanges and secured over the joint by 45 nails extended through the cap and the edges of the flanges.

The invention is shown in the annexed drawings in connection with flat sheets having joints upon opposite edges, and also in

connection with a composite sheet representing six tiles, and having an imitation joint between the rows of tiles.

Figure 1 is a full sized diagram showing the ends of two sheets with their adjacent edges overlapped in readiness to receive the cap. 55 The sheets are broken at the middle of their width, and the roofing board, beneath the same, for want of space upon the drawings. Fig. 2 is a diagram showing the joint of two sheets with the cleat secured by a nail, and 60 the cap secured by the cleat. Fig. 3 is a plan of a sheet with the edges flanged as described. Fig. 4 is a perspective view of the cleat. Fig. 5 is a perspective view of the wooden strip. Fig. 6 is a perspective view of the cap 65 Figs. 5 and 6 being broken to represent an indefinite length; and Fig. 7 represents the joint with a cap nailed over the channels. Fig. 8 shows the roof board with the ends of three roofing sheets having flat edges. Fig. 70 9 shows a cap to cover the same; Fig. 10 a cleat to hold such cap in place, and Fig. 11 a diagram showing the application of the cap and cleat to the flat edges of the flanges. Fig. 12 is an end view of a composite sheet 75 provided with my improved joint, and Fig. 13 is a plan of the same. Figs. 3 and 5 are drawn upon a smaller scale than the other figures.

s is the roofing sheet, and *t* the boards upon 80 which the roof is laid. The flange formed upon each sheet is provided with a sloping side *a* having an edge projected laterally above the level of the sheet, which in Fig. 1 is shown with a downwardly bent portion *b* 85 and an upwardly bent portion *c* forming a V-shaped channel *d* above the level of the sheet.

In Figs. 1 to 7 inclusive, the strip of wood *w* is formed with a V-shaped groove *w'* in the top, corresponding with the shape of the channel *d*, and by forming the opposite edges of the sheet with identical flanges the edges of the flanges may be overlapped in the groove, with one channel inside the other, thus forming a water tight joint.

In applying this invention to a roof, the sheets of metal would sometimes be jointed together in long strips, and passed through

rolls of suitable shape, upon the roof, to produce the flanges described, upon the opposite edges. The strips of wood *w*, cut of any convenient length, would be laid upon the roof, 5 beginning preferably at one edge of the latter, and permitting the strips to move freely upon the roof into the position required to support the joints of the sheets. The edges of the sheets would thus be lapped upon one another until the whole roof was covered, 10 nails *e* being driven through the bottoms of the channels into the strips from time to time to hold the strips and the sheets in their proper position. Such nails would expose 15 the joints to leakage, and where it is necessary to protect the same from the weather, a cap *f* is formed in convenient lengths and adapted to cover the top portion of the flanges above the wooden strip; the edges *f'* of the 20 cap being bent downward to throw the water off of the joint upon the sloping portion *a* of the flanges, whence it would run down upon the sheets as desired. To hold the cap in place without perforating the same, cleats 25 consisting in narrow strips *g* are bent to fit transversely in the bottom of the channel with their ends projected beyond the edges of the cap, as shown in Fig. 4. In Fig. 2, such cleat is shown secured over the joint by a 30 nail *e'* driven through the whole joint and through the strip *w* into the roofing boards *t*. In Fig. 2, the ends of the cleat are shown in dotted lines in their original form, and in full lines bent over the edges of the cap; thus securing 35 the same in place without perforating the cap at any point. The successive sections of the cap would be joined at their ends by lapping them, as would also the roofing sheets, as is common with slates or shingles, 40 or the transverse joints may be made tight by solder if the roof be made very flat. The sloping sides of the flange at the edge of each sheet, forms a space or clearance *a'* between such flange and the upright sides of the strip *w*, 45 and the body of the sheet is thus enabled to expand or contract without any crowding of the sheet upon the parts which form the joint. When the edges of the flanges are formed with V-shaped channels, the engagement of 50 such channels with the groove in the strip tends to lock the joint upon the strip, and thus assist also in preserving the joint in great measure from the strains of expansion and contraction.

55 In Figs. 2 and 6, the cap is shown at the middle of its width concaved, which is done for ornament merely, and serves to produce a pleasing effect when the roof is covered with a series of sheets united by such joints. The 60 cap may be flat, or may be arched without altering its function, which, when its edges extend over the top of the joint, is to fully exclude the weather from the same. This system of jointing sheets may be used for "siding" or for ceilings, in which case the nails *e* would not be exposed so much to the weather,

and the cap may be made narrower than the top of the joint, as shown in Fig. 7, and secured in place by nails *e* driven through the middle line of the cap into the strip *w*. The 70 edges of the flanges may be made flat, as shown in Figs. 8 and 11, in which case the cap is necessarily arched as shown in Fig. 9, and the cleats are preferably formed to extend down the sloping sides a little way as shown 75 in Fig. 10, and in the dotted lines *g'* in Fig. 11. Such a form for the cleats permits the edges of the cap to embrace such sloping sides before it is secured in place by the bent ends 80 of the cleats, as shown in Fig. 11.

Fig. 11 shows the application of the invention to fire proof roofs which are heavily coated with hydraulic cement or analogous plastic material; in the substance of which the strips *w* may be readily bedded as shown 85 in Fig. 11, so as to anchor the roofing sheets to the cement when the sheets are nailed to the strips.

Figs. 12 and 13 show the invention applied to composite sheets, each of which represents 90 a number of shingles, tiles, or other metallic coverings, formed in one piece.

s' represent longitudinal and transverse ridges which imitate a series of earthen tiles overlapped on one another, the margin of the 95 sheet upon the opposite sides being formed with the flanges *a*, *b*, *c*, to produce joints of the same shape as that shown in Fig. 1; and hollow ribs *d'* are pressed in the sheet metal intermediate to the ridges *s'*, to imitate complete joints of the same shape. The surface of the sheet between the several rows of tiles thus presents the same appearance at all points upon the roof, and produces a more perfect imitation of single sheet metal tiles 105 laid with such joints.

The composite sheet can be laid much more rapidly and secured to the roof with less labor than single tiles or strips having corresponding joints.

By the present system of jointing roofing sheets, the necessity of forming any seams upon the flanges is wholly avoided, the sheets are adapted to fit upon one another at either edge, and may be laid with much greater rapidity than where flanges are first formed upon the sheets and afterward interlocked or seamed by a subsequent operation. The ridges formed upon the roof by the breadth of the joint are much more ornamental than the slender ridges formed by the ordinary standing seam, and as the entire roof may be laid without the use of solder or heated cement, the danger of fire is wholly obviated.

I am aware that the edges of sheets have 125 been secured upon wooden strips forming ridges upon the roof, and I do not therefore claim such construction broadly. I am not however aware that any roofing sheet has ever been provided with flanges having the sloping 130 side *a* with the edge *b*, *c*, bent to form a channel *d* above the level of the sheet; nor am I aware

that cleats have ever been secured transversely across the joint and a cap held in place over the joint by the bent ends of the cleats.

I have in another application filed simultaneously herewith and numbered 426,530, claimed roofing sheets with hollow ribs upon their edges and V-shaped channels upon the ribs adapted to overlap like the bent flange *b, c*, herein, and have also shown the cap combined with such joint. Such ribs and channels are not however held above the level of the sheet as claimed herein and cannot therefore be used with the wooden strips *w*. I hereby disclaim the subject matter of the said application.

Having thus set forth the nature of my invention, what I claim herein is—

1. A roofing sheet having flanges formed with the sloping side *a*, and the edge *b, c*, bent to form a channel *d* above the level of the sheet, as and for the purpose set forth.

2. The combination, with the roofing sheets having flanges formed with the sloping side *a*, and edge *b, c* bent to form a V-shaped channel above the level of the sheet, of the strips

w, formed with the groove *w'* having the edges of the flanges overlapped therein and secured by nails, as and for the purpose set forth.

3. The combination, with the wooden strips *w* having the V-shaped groove *w'*, of the roofing sheets having flanges formed with the sloping side *a*, and edges bent into V-shaped channels secured within the groove *w'* by nails, and a cap secured longitudinally over the joint with edges bent downward over the sloping sides of the flange, substantially as herein set forth. 30

4. The combination, with the wooden strips *w*, of the sheets having flanges secured upon the strips by nails, the cleats *g* secured transversely across the joint, and the cap laid upon the cleats and held in place by the bent ends of the same, as and for the purpose set forth. 40

In testimony whereof I have hereunto set my hand in the presence of two subscribing 45 witnesses.

JAMES WHITE.
